TIMER

Alonzo W. Noon, San Diego, Calif., assignor of
one-third to Asa H. Rix and one-third to Roy
A. Noon, both of San Diego, Calif.

Application September 26, 1950, Serial No. 186,718

7 Claims. (Cl. 161—1)

1

The present invention relates to timers in general and particularly to a timer of great accuracy capable of opening and closing electrical circuits. More specifically the invention comprises a timer adapted to control an electrical circuit following a predetermined time delay subsequent to the occurrence of an event and which is instantly reset.

The control of machines, apparatuses, and circuits frequently requires that they be actuated following the occurrence of some determinative action or event. It is frequently necessary to provide a time delay between the determinative event and the actuation of the apparatus, device, or circuit, and where the event is repetitive the time delay should be constant and accurate to a high degree. Timers in which the time delay is effected by forcing a fixed volume of air under a predetermined load through a discharge port or orifice are common. Such devices are of great usefulness but there is particular need for timers of greater accuracy and which are free from variations due to changes in atmospheric conditions, wear, and other variables. It is also important in many controls which are repetitive that the device be reset at great speed in order that it may be ready for immediate reoperation. This requires a timer operating with a time delay in one direction but which is instantly reset.

With an appreciation of the problems characterizing the field of controls it is an object of the present invention to provide a new and improved timer in which a predetermined resultant act is effected at a predetermined time interval following the occurrence of a preselected prior event and in which the time delay interval is free from variations due to exterior conditions.

It is another object of the invention to provide a control timer in which the delay period is extremely accurate and in which the resetting operation is substantially instantaneous.

It is still another object of the invention to provide a new and improved timer control mechanism in which the timer impresses a predetermined time delay between the occurrence of certain operations and in which the unit is re-oriented for a subsequent use in a time interval which is fractional as related to the delay period mentioned.

These and other more specific objects will appear upon reading the following specification and claims and upon considering in connection therewith the attached drawing to which they relate.

Referring now to the drawing in which a preferred embodiment of the invention is illustrated:

Figure 1 is a top plan view of the timer con-

2

structed in accordance with the present invention;

Figure 2 is an end elevational view looking in the direction of the arrows upon the line 2—2 of Figure 1; and

Figure 3 is a section upon the plane of the line 3—3 of Figure 1.

The timer constructed in accordance with the present invention is a relatively simple but highly accurate device. It may be divided broadly into five main parts comprising a driving motor 10; a unidirectional flywheel unit, indicated generally by the reference character 11; a torque spring 12; a control switch, indicated generally by the reference character 13; and a frame, indicated generally by the reference character 14. Driving motor 10 comprises a torque motor which receives current from a circuit comprising leads 6 and 7 the flow of current in which is controlled by a switch 8 the actuation of which is related to the event or occurrence initiating the period known as the time delay period. The motor includes a casing 16 fixedly mounted at one end of the base 17 of frame 14. Its shaft 19 rotates with the unshown armature and extends above the frame base 17 being connected by a collar 21 to an aligned shaft 22 rotatably mounted in an end wall or plate 23 forming a part of frame unit 14.

A large diameter gear 26 is fixed to shaft 22 adjacent collar 21 by its own securing collar 27 and rotates with the shaft which, of course, by virtue of the connection of collar 21, rotates with the motor shaft 19. The torque spring 12 encircles shaft 22 with one of its ends 28 seated fixedly in the frame wall 23 while its opposite end 29 seats fixedly in the gear 26 as by extending into an aperture therein. Spring 12 is a carefully calibrated spring the torque of which is related with accuracy to the mass it is adapted to rotate and to the inertia it must overcome in the operation of the device, as will be further described. Spring 12 is so connected between the fixed frame wall 23 and the gear 26 that it is loaded by the movement of the gear 26 upon the rotation of its shaft 22 when driven by the motor 10. Upon the de-energization of the motor it effects the reverse rotation of the gear.

The purpose of rotation of shaft 22 is to actuate the switch unit 13 which, as is seen in the drawing, is mounted upon the side of frame wall 23 opposite to that of spring 12 and gear 26. It comprises an electrical control switch proper 31 and a displaceable actuating plunger or member 32 which is illustrated as being laterally translatable but which, it is to be understood, may be

pivoted, slidable, or mounted for any suitable motion so long as its displacement actuates the internal contacts of switch proper 31. The latter may be a conventional switch but preferably is of the micro-switch type. The leads 33 and 34 which connect to it are a part of the electrical circuit to be controlled by the timer unit. The switch may be so connected into the circuit as either to close or to open it when actuated.

The operation of switch 31 is accomplished by the displacement of plunger 32 by a lever arm 36 carried fixedly upon the extended end of shaft 22 and so positioned as to make contact with plunger 32 when moving between its end positions as determined by stop pins 38 and 39 which extend outwardly from frame wall 23. Lever 36 has its own securing collar 41 by which it is clamped to shaft 22 and its outer end at its leading edge is chamfered and inclined as to provide a cam surface at 42 where it makes initial contact with switch control plunger 32. With motor 10 energized lever 36 is held against stop 38 but upon the de-energization of the motor the lever rotates with its carrying shaft 22 in a clockwise direction, as viewed in Figure 2, that is, from its position adjacent stop pin 38 toward and into contact with stop pin 39. Before reaching the latter lever 36 makes contact with and actuates switch plunger 32.

To provide the time delay period desired between the occurrence of the event which effects the de-energization of the motor and the actuation of the switch 31, reliance is placed upon the flywheel unit 11. The latter is seen to comprise a relatively large diameter flywheel 44 mounted for free rotation upon a shaft 46 and having a mass which is great as compared to the parts to which it is related. The opposite end of shaft 46 has clamped to it by a collar 45 a toothed pinion 47 in mesh with the large diameter motor- and spring-driven gear 26. The shaft extends parallel to shaft 22 and is mounted for rotation with a minimum of friction by means of bearings 48 countersunk at the outer ends of the bore 49 through which the shaft extends in the end wall 23.

It is desired that the shaft 46 be free to rotate without movement of flywheel 44 during the resetting operation in which the gear 26 is turned by motor 10 to load the spring 12 and in which the actuating lever 36 is being repositioned adjacent stop pin 38. To accomplish this result a unidirectional clutch is provided comprising a circular plate or disc 53 secured by means of its clamping collar 54 to the end of shaft 46 adjacent flywheel 44. Upon diametrically opposite sides of the disc 53 are positioned a pair of smaller discs, indicated generally by the reference character 56, which are eccentrically mounted by means of pins 57 upon the side of flywheel 44 in such positions that their peripheral surfaces contact the peripheral surface of disc 53. Spring elements 58 fixed upon pins 59 also secured to the side of flywheel 44 at all times exert a pressure against the central larger disc 53, the springs being so positioned with respect to the pins 57, which support the discs 56 eccentrically, that the spring force tends to wedge the discs 56 between the pins and the disc 53. The relationship is one characteristic of unidirectional clutches or drives in that upon the rotation of shaft 46 and with it the central driving disc 53 in one direction, clockwise as viewed in Figure 2, the peripheral surface of disc 53 exerts a force upon the discs 56 opposing the

5

forces exerted by their springs 58 and tends to move them from wedging relationship. This clockwise direction of rotation referred to is the direction in which the disc 53 is driven by the motor 10. Upon the rotation of the shaft 46 and disc 53 in the opposite direction, however, that is, counterclockwise as viewed in Figure 2, the frictional force exerted by the central disc 53 upon the contacting smaller discs 56 supplements the forces exerted by the spring elements 58 and the smaller discs are wedged between the central disc and their pivotal pins 57 resulting in a binding, locking action in which relative movement is eliminated and the shaft 46 is clutched to the flywheel 44. This is the action which takes place when the shaft 46 and the driving disc 53 rotate under the force provided by the torque spring 12.

The operation of the timer constructed in accordance with the present invention is believed to be clear from the foregoing. Let it be assumed that the torque motor 10 is energized by current received through its leads 6 and 7, the control switch 8 being in its dotted line closed position illustrated in Figure 1. The motor is so designed and constructed that it can remain energized without injury and the shaft 19 and the connected shaft 22 have been rotated in a counterclockwise direction, as viewed in Figure 2, until the lever 36 is in contact with and is held against the stop pin 38. Let it now be assumed that that event or act occurs which is to initiate the time delay period and as a result thereof switch 8 is opened. Immediately current to motor 10 through the leads 6 and 7 is cut off and the motor is de-energized. Instantly torque spring 12 is free to rotate large gear 26 in a clockwise direction, as viewed in Figure 2, its force no longer being overcome by the motor torque. The initial movement of the gear 26 under the spring force produces rotation at higher speed in gear-connected shaft 46 and with it the driving disc 53, both rotating counterclockwise, as viewed in Figure 2. Immediately the smaller discs 56 are wedged between the driving disc 53 and their individual pivotal pins 57, and the flywheel 44, with its relatively great mass and inertia, is clutched to shaft 46 and the spring 12 is loaded by its flywheel effect. Spring 12 performs its function and rotates shaft 22 at the speed permitted by this load and switch-actuating lever 36 moves in a clockwise direction from its initial position adjacent pin 38 to its final position adjacent pin 39 shown in Figure 2. During this movement its leading chamfered edge 42 has made contact with and has displaced switch-actuating plunger element 32 resulting in the operation of switch 31, and opening or closing of the contacts thereof, whichever may be preferred. The time interval required for the pivotal movement of lever 36 from its initial position adjacent pin 38 into position to actuate the switch element 32 has been determined by the acceleration imparted to shaft 22 by the spring 12 and that, of course, has been determined by the relationship between the torque of the spring and the retarding inertia load provided by the flywheel unit 11. The values of these factors are so selected that the plunger 32 is displaced and the switch 31 actuated at a predetermined time interval following the de-energization of motor 10 and the accompanying instantaneous application of the torque of spring 12.

Let it now be assumed further that the timer has effected its purpose and is to be reset. The switch 8 controlling the circuit of motor 10 is

again closed, that is, is moved to its dotted line position illustrated in Figure 1, and the motor is energized. Motor shaft 19, connected shaft 22, and the lever 36 are instantly snapped to their original position and without any braking effect from flywheel 44. This occurs because of the reversed direction of rotation of shaft 46 and its connected disc 53 with respect to the cooperating smaller discs 56 carried by the flywheel. When rotated by motor 10 shaft 46 rotates in a clockwise direction as viewed in Figure 2 and the frictional force exerted by the peripheral surface of disc 53 upon the peripheral surfaces of discs 56 tends to move them from wedging relationship against the forces exerted by their own spring 58. The disc 53 then merely rides past its points of contact with discs 56 and no movement is imparted to the flywheel. Accordingly, the resetting operation is accomplished instantly and without the braking and the time delay effect of the flywheel. Having reached its original position against the stop 38 lever 36 remains there being held by the motor which remains energized and ready for a subsequent operation upon the recurrence of that act or event which causes the switch 8 to be opened.

While the particular apparatus herein shown and described in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claims.

I claim:

1. In a device of the class described, an element to be controlled, a movable element to actuate said element to be controlled, said movable element being movable between limits, first force-exerting means continuously exerting a force on said movable element to displace it to actuate said element to be controlled, second electrically energized force-exerting means normally energized and exerting a force on said movable element sufficient to prevent its displacement by said first force-exerting means and also sufficient to return said movable element to its initial position against the opposing force of said first force-exerting means, retarding means comprising a mass to retard by its own inertia the speed of displacement of said movable element, and means to connect said retarding means to said movable element upon its displacement by said first force-exerting means only.

2. In a timer of the type adapted to impress a predetermined time delay between an initial act and a subsequent act, a rotatable shaft the position of which is to be controlled to control the occurrence of said subsequent act, resilient means continuously urging said shaft in one direction of rotation, normally energized electrical force-exerting means to rotate said shaft normally opposing the force exerted by said resilient means and holding said shaft against rotation by said resilient means, retarding means comprising a mass to retard by its own inertia the speed of rotation of said shaft, and a clutch to connect said retarding means to said shaft upon the rotation of said shaft by said resilient means only.

3. In a timer of the type adapted to impress a predetermined time delay between an initial act and a subsequent act, a rotatable shaft the position of which is to be controlled to control

the occurrence of said subsequent act, a torque spring urging said shaft in one direction of rotation, a normally energized force exerting electrical unit normally urging said shaft in the opposite direction of rotation with sufficient force to overcome said spring and maintain it in a loaded condition, stops to limit the rotation of said shaft in either direction an inertia mass to retard the acceleration of said shaft, and a clutch to connect said inertia mass to said shaft upon its rotation by said torque spring only.

4. In a timer of the type adapted to impress a predetermined time delay between an initial act and a subsequent act, a rotatable shaft the position of which is to be controlled to control the occurrence of said subsequent act, a torque spring urging said shaft in one direction of rotation, a normally energized electric torque motor opposing the rotational force exerted on said shaft by said spring, said motor exerting a torque sufficiently greater than the torque of said spring as to enable it to snap said shaft to a starting position against the opposition of said spring and to retain it there with said spring in a loaded condition, stops determining the starting and final positions of said shaft, a mass having relatively great inertia as compared to all supplemental forces to retard the acceleration of said shaft, and a clutch to connect said mass to said shaft upon its rotation by said torque spring only.

5. In a timer of the type adapted to impress a predetermined time delay between an initial act and a subsequent act, a rotatable shaft the position of which is to be controlled to control the occurrence of said subsequent act, a torque spring urging said shaft in one direction of rotation, a normally energized torque motor opposing the rotational force exerted on said shaft by said spring, said motor exerting a torque sufficiently greater than the torque of said spring as to enable it to snap said shaft to a starting position against the opposition of said spring and to retain it there, a lever fixed to said shaft, stops fixing the range of pivotal movement of said lever upon the rotation of said shaft, a flywheel, and means connecting said flywheel to said shaft including a unidirectional clutch operative to connect said flywheel to said shaft only upon the rotation of the latter under the actuation of said spring.

6. In a timer of the type adapted to impress a predetermined time delay between an initial act and a subsequent act, a rotatable shaft the position of which is to be controlled to control the occurrence of said subsequent act, a torque spring urging said shaft in one direction of rotation, a normally energized torque motor opposing the rotational force exerted on said shaft by said spring, said motor exerting a torque sufficiently greater than the torque of said spring as to enable it to snap said shaft to a starting position against the opposition of said spring and to retain it there, a lever fixed to said shaft, stops fixing the range of pivotal movement of said lever upon the rotation of said shaft, a circuit-controlling electric switch having an actuating element positioned as to be contacted and actuated by said lever in its pivotal movement from said starting position to said final position, a flywheel to provide an inertia load to said shaft upon the rotational acceleration thereof, and means connecting said flywheel to said shaft including gears to increase the speed of said flywheel relative to the speed of said shaft, and a unidirectional clutch operative to connect said

flywheel to said shaft only upon the rotation of the latter under the actuation of said spring.

7. In a device of the class described, a frame having a base and a wall, a torque motor mounted on said base with its shaft extended toward said wall, a second shaft connected to said motor shaft and extended through said wall, said second shaft fixedly carrying a large gear upon one side of said wall and a lever upon the opposite side, a torque spring encircling said second shaft connected between said wall and said gear to exert a force tending to rotate said second shaft against the force exerted by said motor and adapted to do so upon the de-energization of said motor, stops carried by said wall to limit the travel of said lever and the angular rotation of said second shaft, a circuit-controlling electric switch including an actuating element carried by said wall and extended into the path of said lever to receive an actuating force therefrom, a third rotatable shaft carried by said wall and extended parallel to said first and second shafts, a pinion fixed on said third shaft meshing with said gear on said second shaft, a flywheel freely rotatable

on said third shaft, and a unidirectional clutch to connect said flywheel to said third shaft upon its rotation under the actuation of said spring only.
